Des. 213,539
Patented Mar. 18, 1969

213,539

TOOTHBRUSH CHARGING UNIT AND HOLDER OR THE LIKE

Peter N. Ryckman, Mansfield, and Walton E. Sparks,
Lexington, Ohio, assignors to Westinghouse Electric
Corporation, a corporation of Pennsylvania

Filed Dec. 26, 1967, Ser. No. 9,910

Term of patent 14 years

U.S. Cl. D4—16
Int. Cl. D4—02

FIG. 4.

FIG. 1.

FIG. 2.

FIG. 3.

FIGURE 1 is a perspective view of a toothbrush charging unit and holder or the like embodying our design; FIG. 2 is a front elevational view thereof, the rear view being substantially the same in appearance.

FIG. 3 is a side elevational view thereof; and

FIG. 4 is a top plan view thereof.

The power handle and toothbrushes shown in broken lines in FIGS. 1-4 are included for illustrative purposes only.

We claim:

The ornamental design for a toothbrush charging unit and holder or the like, substantially as shown and described.
